UNITED STATES PATENT OFFICE

MAURICE CRAIG TAYLOR, OF NIAGARA FALLS, NEW YORK, ASSIGNOR TO THE MATHIESON ALKALI WORKS, INC., OF NEW YORK, N. Y., A CORPORATION OF VIRGINIA

DETERGENT COMPOSITION

No Drawing.

Application filed October 24, 1929. Serial No. 402,309.

This invention relates to improvements in saline detergent compositions. The invention provides improved detergent salt mixtures of special value in applications in which 5 bacteriological cleanliness as well as apparent cleanliness is important. The improved detergent salt mixtures of the present invention are mixtures of a detergent alkali metal salt, such as alkali metal phosphates, borates, 10 silicates, fluosilicates, carbonates, sulphates and fluorides, and a stable calcium compound of hypochlorous acid, such as calcium hypochlorite substantially free from calcium chloride, the mixture including but a minor 15 proportion of the calcium compound of hypochlorous acid and consisting mainly of a detergent salt.

In the washing of dairy equipment such as bottles, cans and milking machines and in the 20 washing of equipment used in the preparation of food and containers for food products, for example, bacteriological cleanliness is as important as apparent cleanliness. The conventional detergent salt mixtures are effective 25 to secure apparent cleanliness but not to secure bacteriological cleanliness. However, if the water solution in which such detergent salt mixtures are used includes but a small proportion such as one-twentieth part of an 30 alkali metal hypochlorite, sodium hypochlorite, for example, the solution becomes effective to secure cleanliness in both respects. A proportion of hypochlorite sufficient to provide from 0.01% to 0.3% of available chlorine 35 in the solution is sufficient for ordinary purposes. Sodium hypochlorite, however, is unstable to an extent such that its direct addition to such solutions of detergent salt mixtures is difficult if not impractical. Moreover, 40 the addition of an unstable compound of hypochlorous acid to a detergent salt mixture in the small proportion required is unsatisfactory because of the consequent uncertainty as to the effectiveness of the detergent salt mixture when used to secure bacteriological cleanliness as well as apparent 45 cleanliness.

When dissolved, the improved detergent salt mixtures of the present invention provide 50 a solution containing the required small pro-

portion of, for example, sodium hypochlorite, yet the dry detergent salt mixture, in which form it is kept until used, is free from unstable components.

The invention will be further illustrated 55 by the following example: 3 to 8 pounds of a stable calcium hypochlorite product containing from 60—65% calcium hypochlorite, 35—30% sodium chloride and about 5% calcium chloride, calcium carbonate and calcium 60 chloride, is mixed with 95 pounds of trisodium phosphate monohydrate to form a detergent salt mixture embodying the present invention. In general it is satisfactory to incorporate in the detergent salt mixture an 65 amount of the stable calcium hypochlorite product such that the resulting mixture contains about one-twentieth part of calcium hypochlorite. This proportion, of course, is 70 subject to variation.

The calcium hypochlorite products described in United States Patents Nos. 1,481,039, 1,481,040, 1,713,650, 1,713,654, 1,713,668, 1,713,669, 1716,014, 1,718,284 to 1,718,287, both 75 inclusive, and in applications Serial Nos. 300,148 and 308,885 are especially advantageous in the improved detergent salt mixtures of the present invention because of their stability and solubility.

As will be apparent, the detergent alkali 80 metal salt should be substantially dry, that is, free from water available to effect the reaction between the alkali metal salt and the calcium compound of hypochlorous acid, before the minor proportion of the calcium compound of hypochlorous acid is incorporated in the mixture. If necessary, the detergent salt is dried before the calcium hypochlorite component is incorporated.

The detergent alkali metal salts used in the 85 detergent salt mixtures of this invention are salts of acids forming insoluble calcium salts. Thus, when the improved detergent salt mixture of this invention is dissolved in water, sodium hypochlorite, for example, is formed in solution and the calcium salt corresponding to the detergent salt of the mixture is precipitated. Since the calcium hypochlorite, 90 for example, reacting with the detergent salt to produce sodium hypochlorite, for example, 95 100

in the solution is present in the mixture in but minor proportion only a correspondingly small proportion of the detergent salt is consumed in this reaction leaving the solution mainly a solution of the detergent salt although containing sodium hypochlorite, for example, effective to secure bacteriological cleanliness. The insoluble calcium salt precipitated is similarly present in but such small proportion that it can usually be disregarded. This precipitated calcium salt may, however, be separated from the solution of the detergent salt mixture by decantation or filtration if necessary or desirable.

I claim:

1. A detergent salt mixture forming in water a solution containing a water soluble detergent and a bactericide, the detergent being at least equal in amount to the amount of the bactericide, said mixture comprising a water soluble detergent alkali metal salt of an acid forming an insoluble calcium salt and a minor proportion, with respect to the alkali metal salt, of a stable calcium hypochloride.
2. A detergent salt mixture comprising trisodium phosphate and a minor proportion of a stable calcium hypochlorite.
3. A detergent salt mixture comprising an alkali metal phosphate and a minor proportion of a stable calcium hypochlorite.
4. A detergent salt mixture forming in water a solution containing a water soluble detergent and a bactericide, the detergent being at least equal in amount to the amount of the bactericide, said mixture comprising an alkali metal carbonate and a minor proportion, with respect to the alkali metal carbonate, of a stable calcium hypochlorite.
5. A detergent salt mixture forming in water a solution containing a water soluble detergent and a bactericide, the detergent being at least equal in amount to the amount of the bactericide, said mixture comprising an alkali metal silicate and a minor proportion, with respect to the alkali metal silicate, of a stable calcium hypochlorite.
6. A detergent salt mixture forming in water a solution containing a water soluble detergent and a bactericide, the detergent being at least equal in amount to the amount of the bactericide, said mixture comprising an alkali metal phosphate and a minor proportion, with respect to the alkali metal phosphate, of a stable calcium hypochlorite.

In testimony whereof I affix my signature.
MAURICE CRAIG TAYLOR.
